UNITED STATES PATENT OFFICE.

WILLIAM HINCHLIFFE, OF HUNTSVILLE, ALABAMA, ASSIGNOR TO THE DRAPER COMPANY, OF PORTLAND, MAINE, AND HOPEDALE, MASSACHUSETTS.

SPINNING-SPINDLE.

SPECIFICATION forming part of Letters Patent No. 602,987, dated April 26, 1898.

Application filed November 29, 1897. Serial No. 660,042. (No model.)

To all whom it may concern:

Be it known that I, WILLIAM HINCHLIFFE, of Huntsville, county of Madison, State of Alabama, have invented an Improvement in 5 Spinning-Spindles, of which the following description, in connection with the accompanying drawing, is a specification, like letters and figures on the drawing representing like parts.

10 This invention relates to spinning-spindles; and it has for its object the production of simple and efficient means whereby the retaining-hook may overlap the spindle-whirl to a greater extent to obtain a better purchase, with means for preventing accidental withdrawal of the hook and consequent release of the spindle.

15 The drawing, in elevation and partly in section, represents a spindle with my invention applied thereto.

20 The spindle S, mounted in any suitable bearing, (not shown,) supported in the case A, threaded to receive the nut B to retain it upon the rail B^X, and the whirl W, attached 25 to the spindle, may be and are of usual construction.

The case A is provided with a well-known form of oil-reservoir C to admit oil to the interior of the case.

30 I have herein shown the upturned portion of the reservoir provided on the side toward the spindle with ears c^X, (only one being shown,) in which are independently pivoted the reservoir-cover c and the spindle-retaining hook 35 d. The hook is fulcrumed at d' near its lower end and has a long lip d² to extend over the whirl as far as desired, the extended lower end d³ of the hook bearing against a lug to limit the inward movement of the hook.

It will be noticed that the cover c, fulcrumed 40 on the ears at c', is extended between the latter to form a detent c² to within a short distance of the back of the hook. So long as the cover is in closed position the hook cannot be withdrawn, and any upward pull on the spindle 45 cannot possibly throw the hook back to release the whirl and spindle.

When it is desired to release the spindle, the cover is turned up into dotted-line position, so that the detent c² is moved away from 50 the hook, whereupon the latter can be swung back sufficiently to release the whirl.

While the cover can be lifted independently of and without withdrawing the hook, the latter cannot be moved into inoperative 55 position unless the cover is first lifted.

Having fully described my invention, what I claim, and desire to secure by Letters Patent, is—

1. A supporting-case having an oil-reservoir, a spindle-retaining hook, and an independently-mounted cover for the reservoir, provided with a detent to prevent accidental withdrawal of the hook.

2. A spindle-supporting case having an upturned oil-reservoir provided with ears, a reservoir-cover and a spindle-retaining hook, independently fulcrumed on said ears, and a projecting lug on the cover back of the hook, whereby the latter cannot be withdrawn when 70 the cover is shut.

In testimony whereof I have signed my name to this specification in the presence of two subscribing witnesses.

WILLIAM HINCHLIFFE.
